(57) **CLAIM**

The ornamental design for a dispenser for dispensing a fluid into a nasal cavity, as shown and described.

DESCRIPTION

FIG. 1 is a perspective view from above of one side and one end of a dispenser for dispensing a fluid into a nasal cavity showing our new design;

FIG. 2 is a perspective view from below of opposite side and opposite end thereof;

FIG. 3 is a perspective view from above of one side and one end with parts separated thereof;

FIG. 4 is perspective view from below of opposite side and opposite end with parts separated thereof;

FIG. 5 is a side view thereof;

FIG. 6 is an end view thereof;

FIG. 7 is a plan view thereof;

FIG. 8 is a side view with parts separated thereof;

FIG. 9 is an end view with parts separated thereof;

FIG. 10 is an opposite side view thereof;

FIG. 11 is an opposite end view thereof;

FIG. 12 is an underneath plan view thereof;

FIG. 13 is an opposite side view with parts separated thereof;

FIG. 14 is an opposite end view with parts separated thereof; and,

FIG. 15 is a side view with parts separated thereof, with lever shown in a depressed position.
